UNITED STATES PATENT OFFICE.

CHARLES F. RAYDURE, OF PHILADELPHIA, PENNSYLVANIA.

BURIAL-VAULTING SYSTEM.

1,204,686.

Specification of Letters Patent. Patented Nov. 14, 1916.

Application filed January 18, 1916. Serial No. 72,686.

To all whom it may concern:

Be it known that I, CHARLES F. RAYDURE, a citizen of the United States, residing at the city of Philadelphia, in the county of Philadelphia and State of Pennsylvania, have invented certain new and useful Improvements in Burial-Vaulting Systems, of which the following is a specification.

My invention has relation to a system of building up in an oblong ground opening burial vaulting structures of reinforced concrete or monolithic material independent and separable as structures with respect to each other and each arranged for the reception of a casket or coffin. The structures mounted upon one another without previous preparation in respect to surroundings, yet at the same time arranged so as to be removable for other disposition of the structures with the least time, trouble or disturbance in so doing of the ground opening.

Hitherto the common custom has been to provide an oblong opening in the ground and to build up walls of brick or cement into separate crypts for sliding coffins or caskets thereinto from a point central of the ground opening toward each side. This is expensive and takes time, and the main purpose of my invention is to lessen the time in providing vaulting for a casket or coffin and to simplify the method of such vaulting used either singly or collectively and of a character impervious to moisture and air so that coffins or caskets placed therein are proof against deleterious effects of ground dampness that hitherto wooden boxes or the like were subject to, causing crumbling of the same, while the said reinforced monolithic or cement structures are proof against disintegration by aged confinement in the ground.

The nature, scope and characteristic features of my present invention will be more fully understood from the following description taken in connection with the accompanying drawings forming part hereof, in which—

Figure 1, is a central sectional view of a series of burial vaulting structures in connected operative yet removable relationship in respect to each other and the same moisture and air proof and as illustrated embodying the essential features of my said invention. Fig. 2, is a perspective view, partially broken away of a single reinforced molded concrete or monolithic structure with its removable close fitting cover to pro-

vide a molded reinforced moisture and air proof structure for the reception of a casket or coffin to indefinitely preserve the same; and Fig. 3, is a transverse sectional view of a slightly modified arrangement of the structure of Fig. 1, in respect to the manner as well as means of reinforcing the molded monolithic or cement moisture and air proof structure for the defined purpose.

Referring to the drawings 4, is the oblong ground opening or grave for receiving a series of structures 5, of my said invention. Each molded structure is composed of internal metal means as netting 6, in Figs. 1 and 2 or steel or iron wires, rods or bars 6, as in Fig. 3. The said means 6, is arranged as shown in the drawings in the bottom, sides, ends and cover of the molded structure and against and about which concrete, cement or monolithic substance or material is molded therewith, so as to rigidly adhere thereto and to form a strong substantial structure and in hardening to assume a moisture and air proof condition for the reception of caskets or coffins 7, as clearly shown in Fig. 1. The cover 8, in Figs. 1 and 2, is shown offset on the inner portion to snugly fit down against the inner edge of the body of the reinforced structure, while in Fig. 3, the cover is provided with a tongue 9, fitting a groove 10, provided in the upper edge of the structure to snugly fit the same and thus to provide a moisture and air tight structure with the casket or coffin placed therein, for example, as illustrated in Fig. 1.

It will be seen according to the plan of my invention, safe preservation of the deposited casket or coffin will be assured in reinforced concrete structures and be unaffected by surrounding conditions in which the structures are placed, as their very nature is such as to harden and become more and more impervious to moisture, air or ground dampness the longer remaining in the ground thus preserving indefinitely the coffins or caskets intact, while at the same time affording if occasion requires, ready removal with the least possible time and trouble, owing to the arrangement in character of the structures and their provision with engaging means 11 and 12, to fit firmly against each other, as clearly shown in Fig. 1.

Having thus described the nature and object of my invention, what I claim as new and desire to secure by Letters Patent is:

A burial vault system, consisting of a

series of crypts arranged one above the other and each having a lid with an offset under peripheral surface to fit complementally the offset surface of its crypt and each of said lids having adjacent to the respective ends the provision of grooves to engage tongues formed integral with the bottom of the next in series of said crypts to provide thereby a vault structure with a series of 10 readily removable crypts which are uniformly symmetrical exteriorly throughout

and the said lids by interlocking with the respective crypts and the said crypts with each other, thereby preventing their displacement in said alining relationships, substantially as described.

In witness whereof, I have hereunto set my signature in the presence of the subscribing witness.

CHARLES F. RAYDURE.

Witness:

J. WALTER DOUGLASS.
